CLAIM

We claim the ornamental design for a stool, as shown and described.

DESCRIPTION

FIG. 1 is a front, rear, left, and right side view of a stool embodying the present invention;

FIG. 2 is a top view of the stool of FIG. 1; and,

FIG. 3 is a bottom view of the stool of FIG. 1.

The broken lines shown in the drawings depict portions of the stool that form no part of the claimed design.
